Miriam Schwartz, Bronx, N. Y.

Application February 26, 1945, Serial No. 579,730

3 Claims. (Cl. 36—2.5)

This invention relates to improvements in slippers of the type intended for children's wear.

Slippers of this type have heretofore been made in a form in which the toe portion is constructed to simulate the appearance of an animal head, more specifically, the head of a bunny or rabbit.

My invention is concerned particularly with an improved form of slipper of the character above mentioned, and it is an object of the invention to provide a slipper of that character wherein the upper is formed of a single piece of material so designed that the bunny-simulating portion of the slipper will constitute an integral part of the upper.

Another object of the invention is to provide a slipper possessing the feature of construction above briefly described and further characterized by its ability to retain its bunny-simulating shape at its forward portion without necessity of incorporating any special means to prevent collapse of the bunny head.

Still another object of the invention is to provide a slipper of the character mentioned, which can be produced at low cost and with a minimum of labor.

Other objects and advantages of the invention will become more readily apparent from the detailed description thereof presented herebelow and from the accompanying drawings, in which:

Fig. 1 is a perspective view of a slipper constructed in accordance with the invention, parts being broken away for purpose of clearer illustration;

Fig. 2 is a bottom plan view of the slipper;

Figs. 3 and 4 are transverse cross-sectional views taken respectively along lines 3—3 and 4—4 of Fig. 1, looking in the direction of the arrows;

Fig. 5 is a plan view showing the inner side of a blank constituting the upper of the slipper;

Fig. 6 is a plan view of one end of the blank, showing certain preliminary steps in the formation of the bunny head portion of the slipper according to the invention; and

Fig. 7 is a view, in top plan, of the sole portion of the slipper.

Referring now in detail to the drawings, the slipper embodying my invention is composed essentially of two parts, namely, the upper, designated generally by the numeral 10, and the sole, designated by the numeral 11.

In accordance with one important feature of the invention, the upper 10 is made from a one-piece blank 12, composed of suitable material, desirably sheepskin, configured as illustrated in

Fig. 5. Such a blank may readily be stamped out from a parent sheet of material such as sheepskin, by means of a stamping die having the die knives thereof suitably positioned for the purpose.

As best shown in Fig. 5, the blank 12 comprises an elongated piece of the selected material, configured in symmetrical outline with reference to a transverse median line therethrough. Or, in another manner of speaking, the portion of the blank lying on one side of such a transverse line may be said to constitute a mirror-image of the portion thereof lying on the opposite side of such line.

Thus, the blank has a bottom edge 13 which extends along a slight curve from the mid-point thereof, marked as by a notch 14, toward the opposite ends thereof to the points marked as by notches 15, from the latter of which the edge 13 pursues a more abrupt curve, as indicated at 16, to the terminal points 18 where it joins end edges 20. These end edges 20 are each also formed slightly arcuate and intersect the edge 13 at substantially, or slightly less than, a 90° angle. The other end 21 of each of the edges 20 lies at points along a line located above the edge 13 approximately two-thirds the width of the blank at its transverse median line.

Connecting with each of the end edges 20, at points 21, are outwardly extending edges 23, these latter intersecting the respective edges 20 at an angle of approximately 90° to a tangent of edges 20 at points 21.

From the outer ends 24 of each of the edges 23, the blank is formed with upwardly and inwardly directed curvilinear edges 26 terminating at points 27, from whence there extend, again inwardly and upwardly, slightly curved edge portions 29 which join at 30 with downwardly and inwardly extending edges which are curved as indicated at 32, 33.

A substantially straight horizontal edge 34 extending between the edge portions 33 forms the top edge of the body portion of the blank. The edge 34 is disconnected from the edge portions 33 by means of slits 36 extending into the body portion of the blank along arcuate lines constituting prolongations of the edge portions 33.

Each of the extensions constituted or outlined at each end of the blank by the edges 29, 32 and 33 are provided with slits 38 extending downwardly from the juncture of edges 32 and 33 along arcuate paths as shown, approximately parallel to the edges 29. The slits 38 are also preferably of approximately the same length as the edges 29 and

approximately equal in length to the combined length of each of the respective edges 33 and slits 36. There are thus provided, at these portions of the blank, flaps 40 for a purpose which will hereinafter more fully appear.

As will be apparent, the slits 36, 38 may be formed simultaneously with the operation of die-cutting the blank from a sheet of parent material, by suitably positioning slitting knives in the die. Likewise, the die may be provided with suitable punches to form holes 42 for a purpose to be hereinafter explained, and with suitable punches or other devices for forming the above-mentioned notches 14, 15 as well as holes or other indicia as indicated at 44.

The blank thus formed constitutes a one-piece upper for the slipper of the present invention. In building up the slipper therefrom, the edge 34 is folded over inwardly the full extent permitted by the length of the slits 36 and the folded portion is secured in place by blind stitching the edge 34 to the inside of the body portion of the blank as indicated at 46.

The flaps 40 are also folded inwardly and secured in place near their ends, preferably by small rivets or eyelets, as indicated at 48, passing through the pre-punched holes 42.

As will now be evident, the pointed extensions between each of the folded down flaps 40 and the adjacent edges 33 constitute the ears of a simulated bunny head, while the edges 20, 23, 24 and 26 provide an outline at each end of the blank which, in profile, simulates the head, nose and mouth of the bunny. Further verisimilitude to a bunny head may be achieved by securing buttons 50 at suitable places on the head-simulating portions. These buttons are preferably of the clinch-fastening type as illustrated in Fig. 3, and of a color contrasting with that of the exterior surface of the slipper. They are best positioned a short distance from and about midway the length of each of the edges 26. In this manner, the eyes of the bunny may be quite realistically simulated, accurate positioning of the buttons 50 for that purpose being ensured by the above-mentioned pre-punched holes or other indicia 44.

The upper of the slipper may now be completed from the blank as thus formed and prepared, by folding it transversely upon itself and sewing together, as indicated at 55, the juxtaposed edges 20, 23, 26 and 29. This sewing is preferably done with the upper turned inside out, and with an overseam chain stitch, so that the seam will not be readily discernible to the eye when the sewed upper is turned right side out and the front of the slipper viewed from a reasonable distance.

A particularly noteworthy feature of the invention resides in the fact that when flaps 40 are secured in their infolded position as described and seamed along their meeting edges 29, they serve to prevent lateral spreading of the sides

of the upper and to enable the slipper snugly to fit the foot of the wearer.

The completed upper of the slipper may now be combined with a sole of any suitable material. Desirably, this also may comprise a piece of sheepskin. The sole 11, after being cut or stamped in appropriate size from a parent sheet of the selected material, may be united with the upper 10 by stitching the bottom edge of the previously completed upper to the edge of the sole, as indicated at 58. For this stitching, there is preferably employed an overseam chain stitch and thread of a color which contrasts with that of the outer surface of the sole, as well as with that of the sheepskin or other material employed for the upper, thereby imparting to the slipper an additional attractive feature which may be taken advantage of also for educational or instructive purposes.

It will thus be seen from the above detailed description that the invention provides a slipper of the general type set forth, which may be economically manufactured by combining a sole with a one-piece upper embodying all the elements essential to simulation of a bunny head at its front portion; and that the slipper so constructed is attractive in appearance, comfortable to the wearer, capable of snugly fitting the foot of the wearer, and further characterized by sufficient firmness in the simulated bunny head to retain the shape of the latter throughout the normal period of usage of the slipper.

Although but one embodiment of the invention has been described in detail, it will be apparent that various changes may be made therein without departing from the scope of the invention as defined in the claims hereunto appended.

I claim as my invention:

1. A slipper of the character set forth, comprising an upper and a sole stitched to the bottom edge thereof, said upper being formed of a single piece of flexible material with the opposite ends thereof secured in juxtaposed position at the front of the slipper, one of said ends having an outline which is a mirror image of the outline of the other of said ends, each of said outlines including elements which, in said juxtaposed position, in which the corresponding elements thereof are secured, cooperate to simulate the head, ears and nose of a bunny at the front of the slipper.
2. A slipper as defined in claim 1, further characterized by having flaps formed at the rear of the simulated head, said flaps being folded into and secured to the interior of said upper.
3. A slipper as defined in claim 1, further characterized by having flaps formed as prolongations of the simulated head at the inner end thereof, said flaps extending into the interior of said upper and being secured to one another at their juxtaposed edges and to the interior of the slipper adjacent their free ends.

ERNEST SCHWARTZ.
